UNITED STATES PATENT OFFICE.

EDWARD B. ALLEN, OF BRIDGEPORT, CONNECTICUT, ASSIGNOR TO THE SINGER SEWING MACHINE COMPANY, A CORPORATION OF NEW JERSEY.

THREAD-CUTTING MECHANISM FOR SEWING-MACHINES.

1,333,594.

Specification of Letters Patent. Patented Mar. 16, 1920.

Application filed March 29, 1915. Serial No. 17,595.

To all whom it may concern:

Be it known that I, EDWARD B. ALLEN, a citizen of the United States, residing at Bridgeport, in the county of Fairfield and State of Connecticut, have invented certain new and useful Improvements in Thread-Cutting Mechanisms for Sewing-Machines, of which the following is a specification, reference being had therein to the accompanying drawings.

This invention relates more particularly to thread-cutting means for that class of sewing machines adapted for production of detached successions or groups of stitches; and it has for its primary object the production in a single operation of a group of stitches, such as those affording a binding for the edges of a buttonhole slit, with the ends of the stitching thread or threads concealed from the upper face of the work, and preferably by the covering of one or both ends of the thread by superposed stitches.

In its preferred form, the invention is embodied in a machine provided with a work-holder comprising a lower member and an upper member in the form of a clamping foot pivotally mounted thereon and provided with a plurality of recesses parallel with the work-engaging face of the foot. Within one of said recesses is preferably disposed a combined nipping and cutting blade operative respectively in conjunction with the upper and lower walls of said recess, while an auxiliary cutting blade is disposed in an adjacent recess in a path substantially coincident with the work-engaging face of the clamping foot. The said blades are preferably mounted upon independent fulcrums and receive their operative or thread-engaging movements from suitable springs in opposition to which they are both retracted by means applied to the one and acting through it upon the other. Said blades are maintained in retracted position by means of independent latches which are disengaged to permit nipping and cutting actions, the one by means acting at the completion of a buttonhole stitching operation and the other by means operative in the initial portion of the stitching operation, the former serving to sever the stitching thread leading from the work to the needle at the completion of a stitching period, while the other cuts off close to the work the loose end of needle-

thread used in starting the stitching operation.

During the primary thread-cutting action, the thread leads from the nipping device to the eye of the needle so that the portion of thread detached from the work is then wholly above the nipping elements; but in the descent of the needle for production of the first stitch of a succeeding group, the thread is led by the needle downwardly through the work and over the rearward edges of the cutting elements. Thus in the retraction of the blades succeeding the second cutting action, the short end of thread severed from the work is forcibly carried backward in its simultaneous release by the nipping elements and deposited laterally of the work-holder and the nipping device is thus effectively cleared of thread so that an accumulation thereof, which would impair the effectiveness of the device in subsequent nipping actions, is mechanically prevented. To insure that the loose thread may not be subsequently introduced within the range of action of the stitch-forming devices by the jarring of the work-holder in the stitching operation, or by other means, a blower is preferably provided for applying an air-jet to the clamping foot, thereby providing for the discharge of the detached sections of thread from proximity to the stitch-forming devices.

In the accompanying drawings, the present invention is shown embodied in an eyelet-end buttonhole cutting and stitching machine constructed in substantial accordance with my United States Patent No. 1,048,786, of December 31, 1912, and my Patent No. 1,240,642, of September 18, 1917.

Figure 1 is a rear side elevation of the machine, Fig. 2 a plan thereof with the overhanging arm of the frame removed to expose parts beneath the same, and Fig. 3 is a bottom plan of the machine. Fig. 4 is a plan view of the feed-wheel, the work-holder carrying slide-plate connected therewith and a part of the stop-motion with its tripping means. Fig. 5 is a plan of the tension device with its releasing means and the needle-thread pull-off device. Fig. 6 is a face view of the belt-wheel with the clutch constituting a part of the stop-motion device, and Fig. 7 an edge view of one of the clutch elements. Fig. 8 is a rear end eleva-

tion of the lower portion of the machine, with the base in section.

Fig. 9 is an elevation representing the work-holder with the operating means of the primary thread-cutting and nipping devices in different positions from those of Fig. 1. Fig. 10 is a plan and Fig. 11 an elevation, upon a larger scale, of one of the pairs of work-clamping elements composing the work-holder, showing the thread-nipping and cutting devices with parts of their operating means. Fig. 12 is a bottom view of a portion of the work-clamping foot with the thread-cutting and nipping elements. Fig. 13 is an elevation of the same taken from the front edge, and Fig. 14 is an elevation of the same taken from the rear edge and with the clamping foot in section. Fig. 15 is a representation in face and edge view of the latch for the auxiliary thread-cutting blade. Fig. 16 represents in edge and face view the compound thread-nipping and cutting blade. Fig. 16^a is a face view of the thread-nipping blade-section. Fig. 17 represents in face and edge views the auxiliary cutting blade. Fig. 18 is a plan of the tripping cam-block for the auxiliary thread-cutting blade. Fig. 19 is a front end view of the air-pump and its supporting and actuating means.

The machine frame is shown constructed with the usual hollow base 1 from the rear end of which rises the hollow standard 2 provided with the overhanging tubular member 3. Within suitable bearings 4 is journaled the transverse cutter-actuating shaft 5 disposed in the lower portion of the standard 2 and having mounted loosely upon its forward end the grooved belt-wheel 6 embraced by the driving belt 7 leading from the source of power. As fully disclosed in my said Patent No. 1,048,786, a suitable clutch is provided for connecting the cutter-shaft 5 with the actuating belt-wheel 6 for a single rotation of the latter in each buttonhole producing cycle; and the shaft 5 is provided with suitable cams for imparting tilting movements to the upper and lower cutter-carrying levers 8 and 9 and for imparting traveling movements to their fulcrum-sustaining slide-block 10.

The main-shaft 11 is journaled within and longitudinally of the base 1 and carries adjacent its forward bearing the cam-cylinder 12 with groove 13 entered by the roller-stud 14 depending from the lever 15 swinging upon a fixed fulcrum and connected by the link 16 with the clutch-lever 17 actuating the cramping clutch-dogs 18 having jaws 19 embracing the depending flange 19 of the feed-wheel 20.

The feed-wheel has in its upper face the usual feed-cam groove 21 and side-shift groove 22, the former of which is entered by the roller-stud 23 depending from the

swinging lever 24, which is mounted upon a fixed fulcrum and is provided with the upwardly extending stud 25 coaxial with the stud 23 entering the transverse slot 26 of the slide-frame 27 movable in suitable guideways of the bed 1. Movable fitted to suitable transverse guides of the slide-frame 27 is the slide-plate 28 having upon its underside the block 29 formed with a longitudinal guideway entered by the stud 30 of one end 75 of the rock-lever 31 having a fixed fulcrum intermediate its ends and provided at its opposite end with the roller-stud 32 entering the side-shift cam-groove 22.

Mounted upon and at the forward end of the slide-plate 28 by means of the pivotal pins 33 are the reciprocally movable clamp-plates 34 formed with serrated portions 35 which afford the lower work-engaging jaws of the work-holder opposed to which are the serrated lower faces 36 of the clamping feet 37 affording the upper work-engaging jaws. The feet 37 are pivotally connected in a manner well known with the forward ends of the spring clamp-arms 38 fulcrumed 90 at their opposite ends by means of pins 39 upon the bearing blocks 40 secured upon the respective clamp-plates 34. Mounted within suitable bearings of the blocks 40 are the alined rock-shafts 41 each provided with a 95 cam acting upon its respective clamp-arm 38 in opposition to the lifting spring 42. The rock-shafts 41 are connected together for movement in unison by means of the upwardly extending arms 43 and 44, the one 100 being provided with a lateral pin 43' embraced by a fork 44' of the other.

The clamping foot 37 nearest the back of the machine is provided at its outer end with an extension 45 for supporting the 105 thread-cutting and nipping blades and the parts immediately connected therewith, such extension or support being formed in its lower face with a recess 45' open at the bottom above which is a second recess 45''. The extension 45 is composed of spaced upper and lower plates rigidly secured together by the stud-screws 46 and 47 so as to be relatively yielding where the nipping and cutting blade enters the space between 115 them and they are yieldingly maintained a fixed distance apart at the nipping and cutting points by means of the spacing screw-head 48.

Journaled within an upwardly extending bearing boss 49 of the foot-extension 45 is a rocking pin 50 to the lower end of which is secured, intermediate the head of the axial clamp-screw 51 and the washer 52, the enlarged hub portions of the overlapping 125 blade-sections 53 and 54 constituting a compound thread-nipping and cutting blade, maintained in fixed relation by means of the dowel-pin 55. The outer portion of the operative edge of the nipping blade 53 is 130

- formed with a portion '53' inclined abruptly outward from the adjacent portion to afford an angle for guiding the thread to the nipping point, and has upon its opposite edge 5 a nick '53'' for catching the thread-section upon its disengagement from the relatively fixed nipping jaw so as to insure its removal from the latter in the retraction of the cutting and nipping elements. The edge of the 10 primary cutting element '54' is formed beneath said angle of the nipping element with a concave portion '54' to insure the severing of the thread at the desired point in the length of the blade.
- 15 The component elements of the compound nipping and cutting blade are constructed and operate substantially as shown and described in my United States Patent No. 885,310, of April 21, 1908, excepting in their 20 shapes which are made to accord with other parts of the present improvement. The compound blade '53' '54' is adapted to move within and substantially fill the space or slot '45'' of the support '45', the upper element '53' first coacting yieldingly with the upper wall of the space '45'' in nipping the thread and the lower element '54', having its lower concaved operative edge sharpened, coacting substantially with the abrupt shoulder afforded by the lower and free edge of the space '45'' to sever the nipped thread. While the nipping and primary thread-cutting elements are preferably constructed in 30 separate sections to facilitate their manufacture and maintenance in operative condition, it is evident that the blade need not be made in separable sections, nor the elements referred to be relatively positioned and connected for operative movement in unison as 35 herein represented.
- Secured upon the upper end of the rocking pin '50' is the hub '56' of the crank-arm '57' connected by means of the screw-pin '58' with the flattened forward portion '59' of a 40 bent slide-rod '60' having its rearward portion slidingly fitted within the lug '61' extending laterally from the bearing block '40'. Secured upon the rod '60' is a collar '62' provided with a lateral pin '63' to which is connected one end of a spring '64' having its 45 opposite end attached to the perforated ear '65' of the lug '61'. The spring '64' normally draws the rod backwardly to seat a collar '66' thereon upon the adjacent face of the lug '61' or upon an interposed washer '67', whereby by the primary nipping and cutting blade '53' '54' is maintained yieldingly in advance or operative position, as represented in Fig. 12.
- 50 Secured upon the rod '60' intermediate the collars '62' and '66' by means of the set-screw '68' is a block '69' carrying a roller-stud '70' which is embraced by a fork '71' of the lower arm of a swinging lever '72' fulcrumed intermediate its ends upon the rock-shaft '41' and having upon its upper end the lateral tooth '73' whose upper face is inclined upwardly and forwardly at an acute angle with its adjacent face extending toward the fulcrum point of the lever. The movement 55 of the latch-lever upon its fulcrum in opposition to the stress of the spring '64' obviously causes the endwise movement of the rod '60' and the consequent retraction of the primary cutting and nipping elements preparatory to their action upon the needle-thread at the completion of a stitching operation.
- 56 Journaled upon the stud-screw '46', or a spacing washer surrounding the same, intermediate the component plates of the clamping-foot extension '45' is the hub '74' of the auxiliary cutting blade '75' which is downwardly offset from said hub in such manner as to be movable in a path within the lower recess '45'' of the clamping-foot extension. The blade '75' has near its outer end a concave portion '75' which is sharpened to form a cutting edge for severing the initial end of needle-thread leading from the work to the nipping device. From the hub '74' extends in angular relation with the blade '75' a lateral arm '76' formed with an angular shoulder or tooth '77'. The tooth '77' is adapted to be engaged by 60 the hooked extremity '78' of a latch-arm '79' constituting one member of a plural-armed lever having its hub portion '80' journaled upon the stud-screw '47', or a spacing washer surrounding the same, intermediate the component plates of the clamping-foot extension '45'. The said lever is provided upon the opposite side of said hub with a curved tappet-arm '81' intermediate which and the hub is another lateral arm '82' formed with a 65 groove '83' in its edge farthest from the arm '81'. Coiled around a stud-screw '84' tapped into the upper plate '45' is the body '85' of a spring having one arm '86' resting within the groove '83' of the lever-arm '82' and the other arm '87' bearing upon a pin '88' projecting from the hub portion '74' of the auxiliary cutting blade '75'. By means of this spring, the auxiliary cutting element '75' is normally 70 pressed toward its position of operative engagement with the thread and the latch-lever arm '79' is pressed yieldingly into engagement with the arm '76' for detaining the auxiliary cutting element in retracted position, as represented in Fig. 10.
- 75 The hub '74' of the auxiliary cutting blade carries a second upwardly extending pin '89' whose upper end is disposed in the path of movement of a cam-plate '90' whose upwardly offset shank '91' is secured within a suitable 75 transverse seat formed therefor in the top of the crank '57' by means of the fastening screw '92'. In the turning of the rocking pin '50' for retraction of the primary cutting and nipping elements, the cam-plate '90' engages the 80

pin 89 and acts through the same to shift the auxiliary cutting blade 75 into retracted position wherein it is held by the automatic engagement of the latch-arm 79 with the knife-blade arm 76, as represented in Figs. 2 and 10.

The clamp-arm 38 is shown provided with an apertured bearing lug 93 entered by the forward portion of the bent trip-rod 91 whose forward extremity is disposed in alignment with the latch-lever arm 81. The flattened rearward end of this trip-rod is pivotally connected by means of the stud 95 with the upper arm 96 of an angle-lever fulcrumed at 97 upon the inner face of the bearing block 40 and having a rearwardly extending arm 98 provided in its lower edge with a notch 99 with inclined rearward cam-edge 100, the arm 96 being pressed backwardly for retraction of the trip-rod 94 by means of a spring 101 sustained by the bearing block 40.

The notched extremity of the angle-lever arm 98 normally rests upon a swinging plate 102 pivoted at one end by means of the stud-screw 103 upon a block 104 which is in turn sustained by a member of the base 1 or some other part of the machine fixed relatively to the travel of the work-holder. The plate 102 has at one edge of its upper face the cam-tooth 105 with its operative rearward face 105' upwardly and forwardly inclined similarly to the cam-edge 100 of the notch 99, while its forward face 105'' is inwardly and backwardly inclined, as represented particularly in Figs. 10 and 18. Secured to the end of the block 104 by means of the fastening screw 106 is a spring 107 having a bent arm 108 resting against a stop-pin 109 which is maintained normally in contact with a shoulder 110 afforded by the rabbet formed in the adjacent edge of the block 104, as represented in dotted lines in Fig. 18.

At the beginning of a stitching operation, the cam-tooth 105 is embraced by the notch 99 of the angle-lever arm 98 with its operative face 105' slightly spaced from the cam-edge 100 of the notch 99, as represented in Figs. 10 and 11.

In the travel of the work-holder, and with it, the angle-lever 96 98, during the production of the first few stitches of a buttonhole, the cam-edge 100 encounters the face 105' of the cam-tooth 105 and rides up the latter whereby the angle-lever is tilted and the trip-rod 94 moved into engagement with the latch-lever arm 81, thereby tilting the latch-lever and releasing the auxiliary cutting blade which performs under the action of the spring-arm 87 an operative thread-severing movement across the lead of the thread end extending from the work to the nipper, thereby cutting off the same close to the work. This operative movement is arrested by encounter of the head of a stop-screw 111

carried by an extension of the hub 74 with the upper clamp-foot extension-plate 45. The arm 98 having ridden over the cam-tooth 105 continues to move to the end of its forward travel and then performs its retrograde movement with the work-holder. As its extremity encounters the laterally inclined face 105'' of the cam-tooth, it thrusts the same aside in opposition to its spring 108, as represented in Fig. 18, and upon resuming initial position allows the cam-tooth to snap into its full line position (Fig. 18) in readiness for a succeeding tripping action.

The stitch-forming mechanism of the machine represented in the drawings is substantially the same as that of my Patent No. 1,030,046, of June 18, 1912, as is also the means for turning the same in the stitching of the eyelet-end of the buttonhole. The turning means comprise the endwise movable slide-bars 112 and 113 journaled in suitable bearings sustained by the frame above and below the work-clamp and connected for movement in unison by means of the member 114. While these slide-bars derive their endwise movements from a connection with the cam-wheel 20 provided in its upper face with feed-actuating cam-grooves, as disclosed more fully in said patent, such movements are obviously effected independently of the particular feeding motion defined by said cam-grooves and imparted to the traveling work-holder. The upper slide-bar 112 has fixed thereon the collar 115 provided with the laterally and forwardly extending lug 116 carrying the stud-screw 117.

Fulcrumed upon the stud-screw 117 intermediate its ends is a rock-lever formed with the arched and forwardly extending latch-arm 118 having the hooked forward extremity 119 affording a shoulder for engagement with the upper extremity of the swinging lever 72, and provided with a rearwardly extending arm 120 notched in the extremity of its upper side to receive the stop-screw 121 tapped into the collar 115 against which it is normally held by means of the spring 122 having one arm resting upon the lever-arm 118 and the other upon the lug 116. The lever-arm 120 carries the upwardly extending contact-pin 123 which may be in practice tapped into a threaded aperture of said arm and secured in the desired position of adjustment by means of the set-nut 124.

The stop-motion of the present machine is or may be constructed substantially in accordance with that of my said Patent No. 1,048,786. Adjacent the loose driving pulley 125 is secured upon the main-shaft 11 the hub 126 of the clutch-wheel or disk 127 recessed at one portion of its periphery for the reception of the clutch-plate 128, said wheel having a segmental recess to receive the cam projection 129 of the clutch- 130

ring 130. The clutch-wheel 127 has in its outer face a segmental recess to receive the buffer-spring 131 interposed between one end of said recess and a stud 132 projecting from the inner face of the clutch-ring 130 normally resting against a shoulder afforded by the opposite end of said recess. The clutch-ring is provided with an eccentric or cam projection 133 terminating near the peripher of the clutch-ring in the notch 134 at the opposite side of which the clutch-ring is provided with a lateral cam incline 135.

Mounted in the bracket 136 secured upon the base 1 is the rock-shaft 137 upon which is fixed the hub of the tilting stop lever 138 carrying a spring-pressed block 139 which is formed with the tooth 140 adapted to enter the peripheral notch 134 of the clutch-disk 130. The stop-lever 138 is normally maintained in operative relation with the clutch-disk by means of the spring 141 interposed between the base of the standard 2 and a lateral extension 142 at the upper end of the stop-lever. The rock-shaft 137 has secured thereon the forwardly extending arm 143 carrying the roller 144 normally lying in the path of movement of the cam-sector 145 carried by one of the cam-disks 145 fixed upon the cutter-shaft 5 by means of which the stop-lever 138 is tilted in opposition to its spring as the cutter-shaft completes a rotation for actuation of the button-hole cutter.

Mounted upon a fixed fulcrum within the base 1 is the upwardly extending arched pawl-lever 146 whose depending upper extremity rests normally upon the side of the lever 143 under the action of the spring 147 and is adapted to move above and in latching relation therewith when said lever is depressed. Disposed closely adjacent to the head of the pawl-lever is the extremity of one arm of a tripping lever 148 fulcrumed at 149 and having its other arm provided with the adjustable contact-piece 150 adapted for engagement by the usual tripping stud 151 carried by the feed-wheel 20 to effect the release of the stop-lever 138 and its movement under the action of the spring 141 into stopping relation with the clutch-disk 130. The movement of the stop-lever is timed to present the tooth 140 above the lower portion of the cam projection 133 which lifts the same in opposition to its spring in the braking of the in-shaft and finally descends in entering the peripheral notch 134, effecting the arrest of the clutch-disk and freeing the loose pulley-wheel 125 from the operative pressure of the plate 128 under the action of the cam-projection 129.

As represented in Fig. 4, the cam-wheel 20 is shown provided with a segmental series 65 of ratchet-teeth 20' adapted for engagement

by the forward end of the reciprocating pawl-bar 152 having its rearward end pivotally connected with the crank-arm 153 of a rocking sleeve 154. The sleeve 154 has a rearwardly extending crank-arm 155 connected by a link 156 with a strap 157 embracing an actuating eccentric upon the hub of the loose belt-wheel 125. As described more fully in my Patent No. 1,024,490, of April 30, 1912, the pawl-bar 152 is controlled in its operative relation with the feed-wheel 20 by means of a plural-armed rocker 158 with one arm of which it has a yielding connection, while another arm of said rocker is connected by means of a rod 159 with a 80 stud 160 upon the rock-lever 138; whereby the movement of the rock-lever into and out of stopping position causes the simultaneous movement of the pawl-bar 152 into and out of operative relation with the feed-wheel 85 in contact with the toothed peripheral portion of which it operates to complete a rotation inaugurated by the feeding mechanism comprising the clutch-dogs 18, during which final feed-wheel movement the stitching devices are turned into initial position after a stitching operation.

Mounted upon a lug 161 projecting from the cap-plate 162 of the tubular arm 3 is the tension-stud 163 provided with the tension disks 164 between one of which and the nut 165 is the spring 166 which is controlled in its operation by means of the axial release push pin 167 in a manner well known. The extremity of the pin 167 is 100 adapted for engagement by the inclined operative face of the depending head 168 of the tension release rock-lever 169 mounted intermediate its ends upon the fulcrum stud-screw 170 and having its rearwardly 105 extending arm pivotally connected by means of the screw-pin 171 with the depending bar 172 provided at its lower end with the lateral lip 173 formed with a slot 174 embracing the shank of the screw-stud 175 110 tapped into the lower portion of the standard 2. The bar 172 is normally drawn downwardly by means of a spring 176 having one end hooked in an aperture 177 of said bar and the other end attached to a 115 stud 178 upon the standard 2.

Pivotaly mounted upon the enlarged lower portion of the bar 172 by means of the stud-screw 179 is a plural-armed pawl-lever having a depending arm 180, an upwardly extending arm 181 and a rearwardly extending arm 182, the latter resting normally upon the head of a stop-screw 183 tapped into the bar 172 under the action of the spring 184 carried by the bar 125 172 and having an arm resting upon one edge of the pawl-lever arm 181. The lower end of the pawl-lever arm 180 is adapted to rest upon a stud-pin 185 sustained by the forward arm of a rock-lever 186 fulcrumed 130

intermediate its ends by means of the stud-screw 187 upon the stop-lever extension 142 and having a rearwardly extending arm connected by means of the screw-pin 188 connected at its upper end of a bent link 189 5 with the upper end of a bent link 189 connected at its lower end by means of the screw-pin 190 with the slide-block 139.

In the position of the parts represented in Fig. 1, the block 139 is in its lower or 10 stopping position, and the bar 172 is maintained in its upper position for holding the rock-lever 169 in tension-releasing position wherein the tension-disks are relieved of the pressure of the tension-spring 166. The 15 tilting of the stop-lever 138 to start the stitch-forming and feeding mechanisms carries the stud 185 from beneath the pawl-lever arm 180 and thereby removes the support for the bar 172 which is caused to descend under the action of its spring 176 for 20 discontinuance of the operative engagement of the tension-release pin by the head of the rock-lever 169, thereby causing the tension-spring 166 to resume its normal action upon 25 the tension-disks. The tripping of the stop-motion and consequent return of the stop-lever 138 to stopping position causes the backward movement of the rock-lever 186 and hence the engagement of the stud 30 185 with the forward edge of the pawl-lever arm 180 which is thereby rocked in opposition to its spring 184.

As the block 139 rises under the control 35 of the cam-projection 133 of the clutch-disk 130, the lever 186 is rocked to bring the stud-pin 185 below the bottom of the pawl-lever arm 180 which snaps into normal position beneath the same for positive engagement therewith in the subsequent 40 descent of the block 139 when the tooth 140 enters the notch 134 of the clutch-disk 130 for final arrest of the main-shaft. The rise of the bar 172 under the lifting movement of the rock-lever 186 causes the actuation of 45 the tension-release rock-lever 169 for again opening the tension.

As will be readily understood, it is desirable that the action of the tension upon the needle-thread be resumed preparatory 50 to the beginning of the first stitch-forming cycle of a group. By the disengagement of the tension-releasing bar 172 from its lifting element 186 preparatory to the initial movement of the main-shaft, the tension is 55 closed upon the thread at the same instant by the action of the spring 176 upon the connected tension-release lever 169.

The tension-release rock-lever 169 carries 60 a screw-pin 191 connecting with it the upper end of the depending bent trip rod 192 having intermediate its ends an enlargement provided with the slot 193 embracing the shank of the guiding screw-stud 194 and provided at its lower end with the 65 rearwardly offset cam-head 195 formed in its

forward edge with the bevel 196 and adapted for engagement with the end of the contact-pin 128 carried by the latch-lever arm 120.

As the machine is represented in Fig. 1, 70 the cutter-shaft is in initial position at the completion of an operative rotation wherein the buttonhole cutter has been advanced into the range of action of the stitch-forming mechanism to cut a buttonhole and has 75 been returned to initial position, and the clamp has been closed and spread. Succeeding the engagement of the cam-plate 145' with the roller 144 of the stop-lever arm 143, the stop-lever would be in running position, but in order to show the 80 stitch-forming and feeding mechanisms and their controlling means in initial position the machine is represented as if the stop motion had been immediately tripped after 85 its actuation by the cam-plate 145'.

As the stop-motion is set for stitching, the tension-release rock-lever 169 is tilted as before explained, and the trip-bar 192 is raised into its full-line position as represented partially in Fig. 9. In the initial forward travel of the work-holder, the lever 72 is carried into engagement with the shoulder of the latch-arm 118 and thereby receives a partial tilting movement, the 95 major portion of its throw being performed in the backward movement of the slide-bar 112 for turning the stitching mechanism in the stitching of the eye of the buttonhole. The lever 72 is detained substantially in 100 this position throughout the remainder of the stitching operation, the thread-cutting elements having been thereby retracted as represented in Fig. 10. Upon the final action of the stop-motion at the end of a 105 stitching operation, the tension is opened as before described and simultaneously therewith the trip-bar 192 is thrust downwardly 110 into engagement with the contact-pin 128 and the latch-lever 118 120 tilted, as represented in dotted lines in Fig. 9, for release of the lever 72, thereby permitting the 115 actuation of the primary nipping and cutting blade under the action of its actuating spring 64 for nipping and severing the 120 thread leading from the needle-eye to the last stitch. The tripping of the auxiliary thread-cutter into action is effected in the initial travel of the work-holder during the succeeding buttonhole-producing cycle, as 125 previously described.

Projecting laterally and upwardly from a lug 197 upon the cap-plate 182 is a stud 198 carrying the screw-pin 199 upon which is fulcrumed the rearward end of the pull-off 125 lever 200 which is formed near its fulcrum point with a slot 201 embracing the head of the stud-screw 191 upon the tension-release rock-lever from which the lever 200 derives 130 its operative movements. The lever 200 has 135

at its free end a lateral extension 202 movable across the lead of the thread from the tension device to the top of the hollow needle-bar, and its descent at the end of a stitching operation causes the drawing of slack thread through the tension device for the initial stitch-forming cycle of a succeeding buttonhole stitching operation.

As represented in the drawings, the 10 thread-cutter carrying clamping foot 37 has its lower plate 45 extended laterally beyond the upper plate at the side adjacent the fulcrum-stud 47, its edge being formed with a guard-rib or curb 203 extending from one 15 of the pivot lugs of the foot with the clamp-arm 38 laterally and forwardly, as represented particularly in Fig. 10. Secured upon the forward face of the bearing block 40 for the other clamp-arm 38 is a bent 20 tube 204 having a contracted forward end to form a nozzle 205 disposed near the clamping-foot extension 45 and directed toward the range of movement of the thread-cutting elements, as represented particularly 25 in Fig. 2.

The opposite end of the tube 204 is connected by the flexible tubing 206 with a nipple at the rearward end of an air-pump cylinder 207 sustained by a hanger 208 having a foot 209 which may be secured upon the bottom of the supporting table of the machine. The cylinder 207 has fitted thereto (Fig. 2) a piston 210 whose plunger-rod 211 is provided with a lateral arm 212 to which is connected one end of a pitman 213 attached at its opposite end to a crankpin 214 upon a grooved pulley 215 mounted upon a stud 216 extending laterally from the hanger 208. The pulley 215 is disposed below the pulley 6 and in contact relation with its actuating belt 7 from the source of power from which it derives rotary movement for imparting reciprocatory movements to the piston through the described 45 connections. The operation of the piston 210 within the cylinder 207 causes alternate in-flow and out-flow of air through the tube 204, thereby producing puffs of air upon and around the clamping feet and insuring 50 the ejection of any loose matter in the vicinity of stitching elements through the chute provided by the lower extension plate 45 and guard-rib 203.

In the operation of the machine, the 55 clutch device of the cutter-shaft is first actuated to produce a single rotation of said shaft for cutting the button-hole slit, closing and spreading the work-holder, and actuating the stop-motion for setting the 60 stitch-forming and feeding mechanisms in operation. In the initial travel of the work-holder, the auxiliary thread-cutting device is tripped into action to sever close to the work the initial thread section extending 65 from the work to the nipper. The primary

thread-cutting and nipping blade and the auxiliary cutting blade are then returned from operative to retracted position by the movement of the shifting-lever 72 completed at the end of the eye-stitching operation. 70

The auxiliary cutter is maintained retracted by the latch-lever arm 79 and the primary cutting and nipping blade by the continued engagement of the latch-lever arm 118 with the shift lever 72. Upon the 75 actuation of the stop-motion to arrest the stitch-forming and feeding mechanisms, the tension is released, the pull-off lever is actuated, and the latch-lever 118 120 retracted to permit the actuation of the primary thread-nipping and cutting elements upon the thread in the order named. The feed-wheel 20, having performed a partial rotation under the action of the clutch-dogs 18, completes the rotation under the action 80 of the pawl-bar 152 thereby returning the slide-bars 112 and 113 to initial retracted position, the former carrying with it the latch-lever 118 120, and simultaneously turning the stitch-forming elements into 85 their initial positions.

From the foregoing description it will be observed that the present improvement is not limited to the specific construction and arrangement of the component parts of the 90 thread-nipping means and the primary and auxiliary cutting elements coöperating therewith, nor to the particular actuating and controlling means therefor.

Having thus set forth the nature of the 100 invention, what I claim herein is:—

1. In a sewing machine, in combination, stitch-forming mechanism, means for controlling its period of action, a work-holder comprising upper and lower work-clamping 105 members, a plurality of thread-cutting devices mounted upon the upper clamping member, and means for actuating said thread-cutting devices successively in different stitch-forming cycles of a stitching 110 period.

2. In a sewing machine, in combination, stitch-forming mechanism, means for controlling its period of action, a work-holder comprising upper and lower work-clamping 115 members, operating means connected with the upper work-clamping member for opening and closing the work-holder, a plurality of thread-cutting devices mounted upon the upper clamping member, and means acting 120 independently of said operating means for actuating the thread-cutting devices successively in different stitch-forming cycles of a stitching period.

3. In a sewing machine, in combination, 125 stitch-forming and feeding mechanisms, means for controlling their period of action, a work-support, a plurality of movable thread-cutting devices disposed above the work-support having ranges of action em- 130

bracing the lead of and adapted for engagement with the same thread of the stitch-forming mechanism, means connected with one of said mechanisms for timing the action of one of said devices in severing said thread, and means for setting the other of said devices in motion to sever said thread at another point in its length.

4. In a sewing machine, in combination, stitch-forming and feeding mechanisms, means for controlling their period of action, a plurality of thread-cutting devices, means connected with one of said mechanisms for timing the actuation of one of said devices, and means connected with said controlling means for timing the action of the other of said devices.

5. In a sewing machine, in combination, stitch-forming and feeding mechanisms, means for controlling their period of action, a plurality of thread-cutting devices each including a reciprocating thread-cutting element, means acting during stitching periods for retracting said thread-cutting elements from advance cutting position, means connected with one of said mechanisms for timing the actuation of one of said devices, and means independent thereof for timing the action of the other of said devices.

6. In a sewing machine, in combination, stitch-forming and feeding mechanisms, means for controlling their period of action, a plurality of thread-cutting devices each including a reciprocating thread-cutting element, means acting through one of said cutting devices for retracting the cutting elements of both from advance cutting position, and mutually independent means for effecting the action of said cutting devices successively.

7. In a sewing machine, in combination, stitch-forming and feeding mechanisms, means for controlling their period of action, a plurality of thread cutting devices each including a reciprocating thread-cutting element, means independent of the feed-producing elements of the feeding mechanism and said controlling means for retracting said thread-cutting elements from advance cutting position, means connected with one of said mechanisms for effecting the actuation of one of said devices, and means independent thereof for effecting the action of the other of said devices.

8. In a sewing machine, in combination, stitch-forming and feeding mechanisms, means for controlling their period of action, a plurality of thread-cutting devices each including a reciprocating thread-cutting element, means independent of said mechanisms and connected with one of said thread-cutting elements for effecting the retraction of the latter from advance cutting position, a connection between said cutting elements for effecting the retraction of the other cut-

ting element, means connected with one of said mechanisms for effecting the actuation of one of said devices, and means independent thereof for effecting the action of the other of said devices.

70

9. In a sewing machine, in combination, stitch-forming mechanism, means for controlling its period of action, a work-holder comprising upper and lower work-clamping members, means for producing relative feeding movements between the stitch-forming mechanism and the work-holder, a spring-actuated thread-cutting device mounted upon the upper clamping member, means including a latch for setting and holding it in position for operation, and means controlled by said relative feeding movements and timed to act before the completion of a stitching period for tripping said latch to effect the operation of the thread-cutting device.

75

10. In a sewing machine, in combination, stitch-forming mechanism, a plurality of thread-cutting devices each including a spring-actuated reciprocating thread-cutting element, a latch for maintaining one of said thread-cutting elements in retracted position, a connection between said cutting devices whereby the retraction of one of said cutting elements effects the retraction of the other, retracting means connected with the first-named cutting element, tripping means for said latch, and means for effecting the action of the first-named cutting device.

80

11. In a sewing machine, in combination, stitch-forming mechanism, a work-holder, means for producing relative feeding movements between the stitch-forming mechanism and the work-holder, a plurality of thread-cutting devices mounted upon said work-holder and each including a spring-actuated reciprocating thread-cutting element, a latch for maintaining one of said thread-cutting elements in retracted position, a connection between said cutting devices whereby the retraction of one of said cutting elements effects the retraction of the other, retracting means connected with the first-named cutting element, tripping means for said latch, and means for effecting the action of the first-named cutting device.

85

12. In a sewing machine, the combination with stitch-forming mechanism, of a plurality of thread-cutting devices each including a spring-actuated cutting element, a latch for retaining each of said cutting elements in retracted position, and independently acting tripping means for said latches whereby said cutting devices are caused to operate in succession.

90

13. In a sewing machine, the combination with successively operating mechanisms including stitch-forming mechanism, of a plurality of thread-cutting devices each including a spring-actuated cutting element, a

105

110

115

120

125

130

- latch for retaining each of said cutting elements in retracted position, and tripping means each connected with one of said successively acting mechanisms whereby said 5 latches are successively rendered ineffective.
14. In a sewing machine, in combination, stitch-forming and feeding mechanisms, a stop-motion for controlling their period of action, a plurality of thread-cutting devices 10 each including a reciprocatory cutting element, an operative connection between one of said cutting devices and the feeding mechanism, and an operative connection between another of said cutting devices and 15 the stop-motion.
15. In a sewing machine, in combination, stitch-forming mechanism, a work-holder, means for producing relative feeding movements between the stitch-forming mechanism and the work-holder, a thread-cutting device mounted upon said work-holder and comprising a spring-actuated cutting element, means including a latch and a traveling support therefor movable differentially 20 of said relative traveling movements whereby said cutting element is retracted, and tripping means for said latch.
16. In a sewing machine, in combination, stitch-forming mechanism, a work-holder, 30 means for producing relative feeding movements between the stitch-forming mechanism and the work-holder, a plurality of thread-cutting devices mounted upon said work-holder and each including a spring-actuated reciprocatory thread-cutting element, retracting means for said cutting elements, latches for retaining the cutting elements in retracted position and mounted respectively upon and independently of said 35 work-holder, and means for successively tripping said latches.
17. In a sewing machine, in combination, stitch-forming mechanism, a work-holder, means for opening and closing the same, a 40 tension device, a tension release push-pin connected therewith and adapted to render the tension device ineffective, a tension release rock-lever operable independently of the work-holder opening and closing means 45 and adapted for direct engagement with said push-pin, a thread-cutting device, and means connected with and actuated by said tension release rock-lever for effecting the action of the thread-cutting device.
18. In a sewing machine, in combination, 50 stitch-forming mechanism, a tension device, a tension releaser, a thread-cutting device comprising a spring-actuated cutting element and a detent for holding it in retracted position, means for setting said cutting element in retracted position, and means connected with the tension releaser for disengaging said detent to cause the actuation of 55 said cutting element.
19. In a sewing machine, in combination, 60 stitch-forming mechanism, a thread pull-off device, a thread-cutting device comprising a spring-actuated cutting element and a detent for holding it in retracted position, means for setting said cutting element in 65 retracted position, and means connected with said pull-off device for disengaging said detent to cause the actuation of said cutting element.
20. In a sewing machine, in combination, 70 stitch-forming mechanism, a pull-off device, a thread-cutting device comprising a spring-actuated cutting element and a detent for holding it in retracted position, means for setting said cutting element in retracted position, tripping means for said detent, and 75 an operative connection between said tripping means and said pull-off.
21. In a sewing machine, in combination, 80 stitch-forming mechanism, a tension device, a tension releaser, a pull-off device, a thread-cutting device comprising a spring-actuated cutting element and a detent for holding it in retracted position, means for setting said cutting element in retracted position, tripping means for said detent connected with the tension releaser, and an operative connection between said pull-off device and tension releaser whereby the pull-off device is 85 simultaneously actuated with the tension releaser and said tripping means.
22. In a sewing machine, the combination 90 with stitch-forming mechanism, of a thread-cutting device including a reciprocatory cutting element, means for retracting said cutting element, a latch for retaining said cutting element retracted, a common spring connected with said thread-cutting element and said latch for imparting operative movements thereto, and tripping means for said 95 latch.
23. In a sewing machine, the combination 100 with a work-support and stitch-forming mechanism, of thread-nipping means, primary and auxiliary thread-cutting elements having a range of movement intermediate said nipping means and the work-support, and means for actuating said thread-cutting elements in different stitch-forming cycles and for maintaining the nipping means in 110 operative engagement with the thread throughout a period including said stitch-forming cycles.
24. In a sewing machine, the combination 115 with stitch-forming mechanism, of primary thread-cutting and nipping means, an auxiliary thread-cutting element having a range of movement intermediate said nipping means and the work, means for actuating the primary thread-cutting and nipping means and for maintaining the nipping means effective for more than a complete 125 stitch-forming cycle, and means for actuating the auxiliary cutting element while said nipping means are effective and in a stitch- 130

forming cycle succeeding that in which the primary cutting means operate.

25. In a sewing machine, the combination with a work-support and stitch-forming mechanism, of thread-nipping means, a thread-cutting element movable in a path intermediate the nipping means and the work-support, a second thread-cutting element movable intermediate said nipping means and the path of movement of the first-named cutting element, means for imparting to said thread-nipping means and the second-named thread-cutting element operative thread-engaging movements at the completion of a stitching period, means for actuating the first-named cutting element after the initial stitch-forming cycle of the next succeeding stitching period, and means acting in the last-named stitching period and subsequently to the action of the first-named cutting element for retracting said nipping means and both of said thread-cutting elements.

26. In a sewing machine, the combination with a work-support, stitch-forming mechanism, and a stop-motion for controlling the action of the stitch-forming mechanism, of thread-nipping means, primary and auxiliary thread-cutting elements having a range of movement intermediate said nipping means and the work-support, means for imparting operative thread-engaging movements to the nipping means and the primary thread-cutting element at the completion of a stitching period, means for imparting an operative thread-severing movement to the auxiliary thread-cutting element after an initial stitch-forming cycle of the next succeeding stitching period, and means for retracting the nipping means and one of said cutting elements during the second-named stitching period and thereby dislodging by means of the said thread-cutting element the section of thread previously held by the nipping means.

27. In a sewing machine, the combination with a work-support and stitch-forming mechanism, of thread-nipping means, primary and auxiliary thread-cutting elements having a range of movement intermediate said nipping means and the work-support, means for actuating said thread-cutting elements and the nipping means to sever and hold a section of the stitching thread, means for dislodging from the nipping means said section of thread, and means for effecting the removal of said thread-section from proximity to the stitch-forming mechanism.

28. In a sewing machine, the combination with a work-support and stitch-forming mechanism, of thread-nipping means primary and auxiliary thread-cutting elements having a range of movement intermediate said nipping means and the work-support, means for actuating said thread-cutting ele-

ments and the nipping means to sever and hold a section of the stitching thread, means for dislodging from the nipping means said section of thread, a nozzle directed toward the thread-cutting elements, and means for supplying a current of air to said nozzle.

29. In a sewing machine, the combination with stitch-forming mechanism, a work-holder, and means for producing feeding movements between said stitch-forming mechanism and work-holder, of thread-nipping means and primary and auxiliary thread-cutting elements mounted upon said work-holder, means for imparting to said thread-nipping means and one of the thread-cutting elements operative thread-engaging movements in one stitch-forming cycle and for imparting to the other thread-cutting element an operative movement in a subsequent stitch-forming cycle while the thread-nipping means remains in engagement with the thread, means for imparting retractive movements to the thread-nipping means and to both thread-cutting elements in the second-named stitch-forming cycle, a nozzle sustained in fixed relation with the work-holder during said feeding movements, and means for supplying a current of air to said nozzle.

30. In a sewing machine, the combination with stitch-forming mechanism, a work-holder comprising a work-supporting member and a work-clamping member pivotally mounted thereon, and means for producing relative feeding movements between said stitch-forming mechanism and work-holder, of thread-nipping means and primary and auxiliary thread-cutting elements mounted upon said work-clamping member, means for imparting to said thread-nipping means and to one of the thread-cutting elements operative thread-engaging movements in one stitch-forming cycle and for imparting to the other thread-cutting element an operative movement in a subsequent stitch-forming cycle while the thread-nipping means remains in engagement with the thread, means for imparting retractive movements to the thread-nipping means and to both thread-cutting elements in the second-named stitch-forming cycle, a nozzle sustained upon said work-supporting member and directed toward the thread-cutting elements, and means for supplying a current of air to said nozzle.

31. In a sewing machine, the combination with stitch-forming mechanism, a traveling work-holder comprising a work-supporting member and a work-clamping member pivotally mounted thereon, and means for imparting feeding movements to the work-holder, of thread-nipping means and primary and auxiliary thread-cutting elements mounted upon said work-clamping member,

- means for imparting to said thread-nipping means and to one of the thread-cutting elements operative thread-engaging movements in one stitch-forming cycle and for imparting to the other thread-cutting element an operative movement in a subsequent stitch-forming cycle while the thread-nipping means remains in engagement with the thread, means for imparting retractive movements to the thread-nipping means and to both thread-cutting elements in the second-named stitch-forming cycle, a nozzle sustained upon said work-supporting member and directed toward the thread-cutting elements, an air-pump mounted upon a fixed part of the machine, and a flexible connection between said air-pump and said nozzle.
32. In a sewing machine, the combination with stitch-forming mechanism, and a work-holder comprising a clamping foot adapted to rest upon the work, of a thread-nipping device sustained by said foot in close proximity to its work-engaging face, a thread-cutting element for severing the thread between said nipping device and the work, and an auxiliary thread-cutting element movable in a path intermediate said thread-nipping device and the work and substantially in contact with the latter.
33. In a sewing machine, the combination with stitch-forming mechanism, of a plurality of thread-cutting devices each including a spring-actuated cutting element, latches for normally restraining said cutting elements against movement under the action of their respective springs, means operatively connected with moving parts of said machine for compressing said springs, and successively acting tripping means for said latches.
34. In a sewing machine, the combination with stitch-forming mechanism and work-feeding mechanism including a traveling work-holder and a feed-wheel for imparting operative movements thereto, of a plurality of thread-cutting devices each including a spring-actuated cutting element, latches for retaining said cutting elements respectively in retracted position, means connected with said feed-wheel for setting said cutting elements in retracted position in opposition to their respective springs, and successively acting tripping means for said latches.
35. In a sewing machine, in combination, stitch-forming mechanism, nipping means adapted to grip a thread, a primary thread-cutting device, an auxiliary thread-cutting device comprising a cutting element performing movements relatively to said nipping means, and actuating and controlling means for said nipping means and thread-cutting devices timed to effect the nipping of said thread and the repeated cutting of the same while subjected to a single gripping action of the nipping means.
36. In a sewing machine, in combination, stitch-forming mechanism, a thread-nipping device, a plurality of thread-cutting devices adapted to act upon the same thread and of which one comprises an element adapted to perform operative thread-engaging movements relative to said thread-nipping device, and actuating and controlling means for said thread-nipping and cutting devices timed to actuate the nipper to nip the needle-thread and thereafter subject the nipped needle-thread to the action of the cutting devices in succession while the thread remains held by the nipping device.
37. In a sewing machine, the combination with stitch-forming mechanism, of a plurality of thread cutting devices each including a spring-actuated cutting element having a range of action embracing the same thread and disposed at a different distance from the work than that of the other cutting device, and means for operating said cutting devices respectively in succession.
38. In a sewing machine, the combination with stitch-forming mechanism including a reciprocating needle, and a work-support, of a plurality of thread-cutting devices disposed above the work-support and each including a spring-actuated cutting element having a range of action embracing the needle thread and disposed at a different distance from the work than that of the other cutting device, and means for operating said cutting devices respectively in succession.
39. In a sewing machine, in combination, stitch-forming mechanism including a reciprocating needle, means for nipping and severing the needle-thread at the end of a stitching operation, an auxiliary thread-severing device, and means for moving said auxiliary thread-severing device across the lead of the nipped needle-thread end while the latter is held nipped to sever the waste end of needle-thread at the upper side of the work during the next succeeding stitching operation.
